G. Page,

Horse Power.

Patented Sep. 28, 1831.

6768X George Page of Keene, New Hampshire
Sept 28 1831

Letters Patent

The Schedule referred to in the Letters Patent and making part of
the same containing a description in the words of the said George Page
himself of his improvement in the application of horse, and other ani-
mal power to machinery

To all to whom these presents shall come, Be it known that I
George Page of Keene in the County of Cheshire and State of New Hamp-
shire, have invented a new and useful improvement in the application
of Horse power, to move machinery for sawing wood, for pulling boats,
grinding grain and other purposes, and that the following is a full
and exact description of the construction and operation of the said
improvement as invented by me.

The improvement consists in the construction and use of a band
which may be called an inclined band. It may be constructed for
one Horse or for as many Horses as the machinery to be moved may
require. When intended for one Horse it may be made and used
as follows. In the first place make a band of leather, about eighteen
inches wide, and measuring, its whole length, from seventeen to twenty
feet long. It may be of one thickness or of two or three thicknesses
several thicknesses being joined together. If of one thickness, two narrow strips, two or
three inches wide should be thonged to each edge on the outward side
through which the bolts, afterward, mentioned are to be inserted.
This side should then be covered its whole length with pieces of plank
or board about six inches thick about six inches wide, and about
six inches longer than the band is wide. Each piece should be fast-
ened to the band by bolts, the bolts passing through the edges of the
band, through the strips of leather, if strips be used, and through
the middle of the pieces of plank or board. An axle somewhat
longer than these pieces is bored into and strongly bolted to each, on
the outward side, and within an inch or two of the forward edge.
On each end of every axle is placed a cast iron wheel, in diameter

about a quarter of an inch less than the width of the pieces of plank, and ~~one~~ made strong enough to bear a horse and the band. Over these pieces of plank, are placed and fastened by bolts or screws, another set of the same size and so placed, as that the edges shall be exactly over the middle or centre of the other. By placing this outward set thus, the band is made more firm and steady under the tread of the horse. The band passes around two cylinders or drums which are horizontal. These cylinders are about twenty two inches in diameter; nearly the same length as the plank, and are placed at a sufficient distance to take up the band. One which may be called the forward cylinder, is raised one foot a little more or less higher than the other. To either end of either axle passing through these cylinders, is attached a gear of proper size to produce the speed required. At each end of the axle or axle of either of either of the cylinders or drums, a screw should be so placed that the axle may be moved forward or backward at pleasure when it may be necessary to tighten or loosen the band.

For the cart to run wheels aforesaid to run on, a rail way is placed the rails extending from the centre of one cylinder to the centre of the other, having the same inclination as the band, and placed at a proper distance from each other for the wheels to run on. In order to keep the band in place, these rails, or the wheels, should have grooves or rabbets. The height of the rail way must be such that that part of the band which is uppermost, when it recedes will not sag.

The horse is placed on this band, his head towards the forward cylinder. His harness must be similar to a chain harness.

The whippletree is attached to a staff firmly fastened behind him, and the breeching, which is essential is fastened to something at his sides or forward as may be most convenient. The height of the staff is important and must be regulated by the height of the horse. It may be placed a little lower than the ordinary line of draught. This should be placed on each side of the horse to keep him as near as may be on the middle of the

middle of the band. The stepping of the Horse assisted by his weight moves the band, and the moving of the band causes the cylinder to revolve and thus gives motion to the machinery.

The dimensions above given may be larger, or smaller according to the pleasure of the builder, as to the power requisite to move the machinery, a proper proportion being observed.

When two or more Horses are to be used the band may be made wide, and the horses placed abreast of each other, or it may be made long and one placed behind another. Instead of leather, chains may be used, and cast iron wheels may be substituted for cylinders or drums, with eyes to plug into the holes of the chain, and instead of Horses other animal power may be used.

The machine may be so constructed that one or both of the cylinders, and one or both of the railings may be raised or lowered at pleasure. By increasing the inclination of the band to a certain extent, the power of the Horse will be increased, and by laying the band level when the machine is stopped the horse will be enabled to stand at ease. By increasing the diameter of the wheel, which to support the band the power of the horse will be increased in proportion, but in that case the plants must be made proportionably wider.

The improvement which I claim as my invention, and for which I ask an exclusive privilege, is in the application of Horse or other animal power to move machinery for sawing wood propelling boats, grinding grain and for other purposes by an inclined Band operating in manner above described.
